H. RESCH

TYPEWRITING MACHINE

Filed August 14, 1924

70 Inventor:
7.6. Henry Reach
by D. B. Stickney
Attorney

UNITED STATES PATENT OFFICE.

HENRY RESCH, OF BAYONNE, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed August 14, 1924. Serial No. 731,931.

This invention relates to typewriting machines, and more particularly to means for holding work-sheets on the collating tables used in the Underwood bookkeeping machines.

These work-sheets are ordinarily held in position on the collating tables by means of a clamping device having arms which are arranged to grip the work-sheet. Owing to the character of the work to be held and the manner of mounting said gripping arms, it frequently happens, because of inaccuracies of manufacture, or by accident, that these gripping arms do not come into proper contact with the paper-supporting table, with the result that the work-sheets slip out of position. Furthermore, the surface of the table for supporting the work-sheets is usually smooth and the work-sheets have a tendency to slip from their position thereon. One of the features of this invention is the provision of a clamping device that will positively hold the work-sheets in position on their supporting table. This is done by a pair of self-equalizing or adjusting gripping arms, one of which is yieldingly mounted, so that it can adjust itself relatively to the other arm, so that both come into positive contact with the work-sheets, with the result that said work-sheets are more effectively held between the gripping arms and the supporting table.

Another feature of the present invention is the provision of means on the collating table whereby a gripping surface is afforded. This is accomplished by mounting strips of rubber on the surface of the table at the points thereon where the gripping arms contact therewith, which insures a firm grip between the gripping arms and the table.

Other features and advantages will hereinafter appear.

In the accompanying drawings,

Figure 1 is a front view of a typewriter platen and associated parts with the present invention applied thereto.

Figure 2 is a vertical sectional view taken through the right-hand table-section shown in Figure 1 and looking to the right.

Figure 3 is a detail view showing how the gripping arms are mounted.

Figure 4 is a detail view showing the upper gripping arm in effective position.

Figure 5 is a detail view showing the upper gripping arm in ineffective position.

Figure 6 is a fragmentary front view showing how the rubber strips are mounted on the table.

Figure 7 is a detail view showing how the upper gripping arm is mounted adjustably on its shaft.

As is usual a platen 10 is mounted on a shaft 11 which is journaled in platen-frames 12 and 13. Secured to one end of shaft 11 is a hand-wheel 14 for rotating the platen. Co-operating with a rear or main table 15 are the usual front and rear rolls 16 and 17, respectively, to feed and guide work underneath and around the platen 10.

Fixedly mounted on the platen-frames 12 and 13, by means of screws 18 and 19, respectively, and extending therebetween and above the platen 10, is a table-supporting bar 20. Mounted on said bar 20 is an auxiliary table for holding work-sheets, consisting of a left-hand section 21 and a right-hand section 22. Said table-sections 21 and 22 may be adjusted laterally by means of the slots 23 and the screws 24 operating therein. The left edge of table-section 21 is upturned to form a flange or guide 25. The right edge of table-section 22 is also upturned to form a flange or guide 26. These sections 21 and 22 are used in typewriting machines for bookkeeping purposes to support a work-sheet 27, the printed matter on which is duplicated on a record or proof sheet 28.

It is one purpose of the present invention to provide means for effectively holding the work-sheet 27 on the auxiliary table-sections 21 and 22. To accomplish this, there is fixed to the lower end of the flange or guide 26 a paper-clamp 29, the body portion 30 of which is provided with upstanding ears 31 and 32. Journaled in these ears 31 and 32 is a shaft 33. Fixedly mounted on said shaft 33, at one end thereof, adjacent ear 32, is a paper-gripping arm 34. This arm 34 is provided with a paper-gripping pad 35 at its point of contact, and is further provided with a pin 36. The adjacent ear 32 also is provided with a pin 37. Fastened

to said pins 36 and 37 is spiral spring 38 so positioned relatively to the pivotal point of said arm 34 that it will hold said arm 34 in either operative or inoperative position.

Fixed on the other end of shaft 33 is a lever 39 which terminates in a finger-piece 40 for rocking said shaft 33. The shaft 33 at its end adjacent the lever 39 is provided with flat portions 41 and 42 and round portions 43 and 44, and terminates in a reduced cylindrical portion 45. This reduced portion 45 is provided with a bore 46 for a purpose which will appear. Mounted on said shaft 33 at its end where it is provided with said flat and round portions is another paper-gripping arm 47. Said arm 47 is provided with an opening having flat sides 48 and 49 and round sides 50 and 51, which opening is slightly larger than said shaft 33 at the point where said arm 47 is mounted thereon, as will be seen from Figure 7. By reason of this construction, a slight movement between shaft 33 and gripping arm 47 is permitted, which relative movement enables said arm 47 to adjust itself and more firmly grip the work-sheet 27 with its gripping pad 52. Said arm 47 also carries a pin 53. A spiral spring 54, with one end fastened to said pin 53 and its other end fastened to guide 26, as indicated at 55, holds said arm in either operative or inoperative position. When said arm 47 is mounted in its proper position on said shaft 33, the reduced cylindrical portion 45 of said shaft passes freely through ear 31 of body portion 30, into the bore 46 of which is secured a screw 56.

For the purpose of making the clamping operation more effective, in accordance with the present invention, a gripping surface is provided on one of the table-sections. Adjacent the right edge of the table-section 22 and at the points thereon where the gripping pads 35 and 52 come in contact with said table-section 22, lips 57 are formed on said table-section 22. Mounted on each of said lips 57 is a rubber strip 58. As will be apparent from Figure 2, when the gripping arms 34 and 47 are in operative position, their pads 35 and 52, respectively, are in contact with said strips 58, holding the work-sheet 27 tightly therebetween.

In operation, the proof-sheet 28 is firmly held against the platen 10 by means of the paper-rolls 59, and the work-sheet 27 positively held in position on the table-sections 21 and 22 by means of the arms 34 and 47 co-operating with the rubber strips 58, which arms are snapped into effective and ineffective positions by means of the lever 39 and springs 38 and 54. The slight movement between the arm 47 and the shaft 33 permits the former to adjust itself in order to come into positive contact with the strip 58.

Variations may be resorted to within the scope of the invention and portions of the improvements may be used without other.

Having thus described my invention I claim:

1. In a typewriting machine, in combination, a revoluble platen, a main table for supporting a work-sheet, an auxiliary table for supporting a second work-sheet, and a clamp for holding said second work-sheet on said auxiliary table, said clamp including a pair of gripping arms mounted on a shaft, one of said arms being fixedly mounted on said shaft, and the other of said arms being mounted to rock slightly relative to said shaft to permit said last-mentioned arm to adjust itself to effectively grip said second-work-sheet.

2. In a typewriting machine, in combination, a revoluble platen, a main table for supporting a work-sheet, an auxiliary table for supporting a second work-sheet, a clamp for holding said second sheet on said auxiliary table, said clamp comprising a body portion, a shaft journaled in said body portion, and a pair of gripping arms mounted on said shaft, means to rock said arms into either effective or ineffective position, means to hold said gripping arms in either effective or ineffective position, means carried by said auxiliary table to provide a gripping surface thereon, and means to permit adjustment of one of said gripping arms on the shaft to effectively grip the second work-sheet.

3. In a typewriting machine, in combination, a revoluble platen, a main table for supporting a work-sheet, an auxiliary table for supporting a second work-sheet, a clamp for holding said second sheet on said auxiliary table, said clamp including a body portion, a shaft journaled in said body portion, and a pair of gripping arms mounted on said shaft, means to rock said arms into either effective or ineffective position, said last-mentioned means comprising a lever fixedly mounted on said shaft, said lever terminating in a finger-piece, means to hold said arms in either effective or ineffective position, means carried by said auxiliary table to provide a gripping surface thereon, and means to permit adjustment of one of said gripping arms on the shaft to effectively grip said second work-sheet.

4. In a typewriting machine, in combination, a revoluble platen, a main table for supporting a work-sheet, an auxiliary table for supporting a second work-sheet, a clamp for holding said second work-sheet on said auxiliary table, said clamp comprising a body portion, a shaft journaled in said body portion, and a pair of gripping arms mounted in said shaft, means to rock said arms into either effective or ineffective position, means to hold said arms in either effective

- or ineffective position, said last-named means comprising a spring mounted on each of said arms so positioned relatively to the pivotal point of said arms as to hold them 5 in either effective or ineffective position, means carried by said auxiliary table to provide a gripping surface thereon, and means to permit adjustment of one of said gripping arms on the shaft to effectively grip 10 said second work-sheet.
5. In a typewriting machine, in combination, a main table for supporting a work-sheet, an auxiliary table for supporting a second work-sheet, a clamp for holding said second sheet on said auxiliary table, said clamp comprising a body portion, a shaft journaled in said body portion, and a pair of gripping arms mounted on said shaft, means to rock said arm into either effective or ineffective 15 position, means to hold said gripping arms in either effective or ineffective position, means carried by said auxiliary table to provide a gripping surface thereon, said last-named means comprising strips of rubber 20 mounted on said auxiliary table at the points thereon where the gripping arms come in contact therewith, and means to permit adjustment of one of said gripping arms on the shaft to effectively grip said second 25 work-sheet.
6. In a typewriting machine, in combination, a revolute platen, a main table for supporting a work-sheet, an auxiliary table for supporting a second work-sheet, a clamp for holding said second work-sheet on said auxiliary table, said clamp comprising a body portion, a shaft journaled in said body 30 portion, and a pair of gripping arms carried by said shaft, one of said arms being mounted fixedly on said shaft, and the other of said arms being mounted to rock slightly relatively to said shaft to permit adjustment thereon, means to rock said arms into either effective or ineffective position, means to hold said gripping arms in either effective or ineffective position, and means carried by 35 said auxiliary table to provide a gripping surface thereon.
7. In a typewriting machine, in combination, a revolute platen, a main table for holding a work-sheet, an auxiliary table for holding a second work-sheet, a clamping device carried by said auxiliary table, said device including a pair of gripping arms, and rubber pads carried by said arms at their 40 points of contact, lips formed on said auxiliary table at the points thereon where the gripping arms contact therewith, and rubber strips mounted on said lips to co-operate with said gripping arms to hold said second work-sheet between said arms and said strips.
8. In a typewriting machine, a revolute platen, a main table for supporting a work- 45 sheet, an auxiliary table for supporting a second work-sheet, a clamp for holding said second work-sheet on said auxiliary table, said clamp including a body portion, a shaft journaled in said body portion, and a pair of gripping arms carried by said shaft, one of said arms mounted fixedly on said shaft, and the other arm mounted to rock relatively to said shaft to permit said last-mentioned arm to adjust itself to more effectively grip 50 said second work-sheet, and a rubber pad carried by each of said arms at its point of contact, and means carried by said auxiliary table to provide a gripping surface thereon to co-operate with the clamp to firmly grip said second work-sheet.
9. In a typewriting machine, a revolute platen, a main table for supporting a work-sheet, an auxiliary table for supporting a second work-sheet, a clamp for holding said second work-sheet on said auxiliary table, said clamp including a body portion, a shaft journaled in said body portion, and a pair of gripping arms carried by said shaft, one of said arms mounted fixedly on said shaft, and the other mounted to rock relatively to 55 said shaft to permit said last-mentioned arm to adjust itself to more effectively grip said second work-sheet, and a rubber pad carried by each of said arms at its point of contact, and means carried by said auxiliary table to provide a gripping surface thereon to co-operate with the clamp to firmly grip said second work-sheet, said means comprising rubber strips mounted on said auxiliary table at the points thereon where the gripping arms come in contact therewith.
10. In a typewriting machine, a clamp for holding a work-sheet thereon consisting of a body portion, ears formed on said body portion, a shaft journaled in said ears, a pair of gripping arms carried by said shaft, a lever fixedly mounted on said shaft to rock said arms into either effective or ineffective position, springs carried by each of said arms to hold the same in either effective or ineffective position, and means to permit one of said arms to adjust itself on the shaft to effectively grip the work-sheet.
11. In a typewriting machine, a clamp for holding a work-sheet thereon, consisting of a body portion, ears formed on said body portion, a shaft journaled in said ears, a pair of gripping arms carried by said shaft, one of said gripping arms mounted rigidly on said shaft, and the other of said arms mounted to rock slightly relatively to said shaft to adjust itself to firmly grip said work-sheet, a lever fixedly mounted on said shaft to rock said arms into either effective or ineffective position, and springs carried by each of said arms to hold the same in either effective or ineffective position.

HENRY RESCH.
